UNITED STATES PATENT OFFICE.

PETER ROVANO, OF CHICAGO, ILLINOIS.

FUNNEL.

Application filed November 9, 1927. Serial No. 232,005.

This invention relates to new and useful improvements in funnels and more particularly to an attachment for funnels, whereby to not only provide an air inlet for the discharge end of the funnel, but provide outlet means for liquid material being passed through the funnel, so that in filling a vessel the liquid material will not be wasted.

One of the objects of the invention is the provision of a funnel attachment that can be used for conveying the liquid from a filled receptacle to an adjacent receptacle, so that the liquid will not be spilled from the receptacle being filled and wasted.

Another object of the invention is the provision of a washer attachment for this particular type of funnel which is of the sleeve type and of various sizes so that the funnel can be readily used in connection with receptacles having different sized filling openings.

With the above and other objects in view, the invention consists in the novel features of construction, the combination and arrangement of parts hereinafter more fully set forth, pointed out in the claims and shown in the accompanying drawings, in which

Figure 1 is a vertical sectional view of my improved funnel showing its application, and

Figure 2 is a cross sectional view on the line 2—2 of Figure 1.

Referring now more particularly to the drawings wherein various numerals are used to designate the several parts throughout the views 1 indicates a container or rather portion thereof which is provided with an inlet opening 2 for receiving the discharge end 3 of the funnel 4. The discharge end 3 of the funnel is tapering in form as is the usual construction of funnels of this type and formed in one wall at a point adjacent its small end with an opening, while the body of the funnel is formed with a similar opening on the same side of the funnel.

A vent tube 5 has its inner end fitted in the opening in the discharge end of the funnel while the other end of the tube is passed out through the opening in the body of the funnel and connected with a flexible tube 6 which may either form an air vent or be used as an overflow to convey the liquid to an adjacent receptacle. Thus should the receptacle become filled quickly

the overflow beyond a certain point may be readily conveyed to an adjacent receptacle.

As a general rule, these funnels are used in filling receptacles formed with different size openings and in order to provide means whereby the funnel may be properly fitted to these openings I provide a tapering washer collar 7, which fits over the discharge end of the funnel, as shown in Figure 1 with its lower end fitting closely around the end 3 and resting upon an annular bead 8 preferably of rubber as disclosed. The upper end of this collar is closed by means of an inwardly extending annular flange 9 which engages the upper part of the discharge end of the funnel. The bead 8 can be used for supporting the funnel when the funnel is used for filling a small neck bottle or similar receptacle.

The collar 7 is provided in various sizes especially with respect to the exterior thereof, so that any size collar may be readily applied according to the size opening into which the discharge end of the funnel is to be fitted, so that the funnel can be readily used with various types of receptacles having different size openings. It will be readily apparent from the foregoing, that when the funnel is placed in position as shown in Figure 1, and the filling operation is proceeded with, the tube 5 provides a suitable vent to permit air to escape from the receptacle being filled. When the liquid being placed in the receptacle has nearly reached the top it will pass out through the tube 5 and be directed into an adjacent receptacle by means of the tube 6, thus avoiding waste of material through overflow of the receptacle being filled. The device is extremely simple in construction and can be manufactured at a very low cost.

While I have shown and described the preferred embodiment of my invention, it will be readily apparent that various changes and alterations may be carried out without departing from the spirit of the invention or the scope of the appended claims.

I claim as my invention:

1. A funnel including a tapering body, a tapering discharge portion at the smaller end of the body, a vent tube communicating with the exterior of the body and discharge portion at their smaller ends, an annular yieldable bead surrounding the discharge

portion adjacent its smaller end, a tapering collar surrounding the discharge portion with its smaller end bearing against the outer wall of said discharge portion and engaging the bead, and an annular inturned flange at the larger end of the collar engaging the junction of the body of the funnel and the discharge portion.

2. In a device of the class described and in combination, a funnel including a tapering body, a tapering discharge portion at the smaller end of the body, a vent tube communicating with the exterior of the body and discharge portion at their smaller ends,

an outlet tube connected to the outer end 15 of the vent tube, an annular yieldable bead surrounding the discharge portion adjacent its smaller end, a tapering collar surrounding the discharge portion with its smaller end bearing against the outer wall of said 20 discharge portion and engaging the bead, and an annular inturned flange at the larger end of the collar engaging the junction of the body of the funnel and the discharge portion.

In witness whereof I have hereunto set my hand this 26th day of Oct. 1927.

PETER ROVANO.
